CLAIM

The ornamental design for a ceiling fan light kit, as shown and described.

DESCRIPTION

FIG. 1 is a bottom perspective view of a ceiling fan light kit showing my new design, shown in the environment of a ceiling fan;

FIG. 2 is a top perspective view of the ceiling fan light kit of FIG. 1, but shown without the ceiling fan environment; FIG. 3 is a top view thereof;

FIG. 4 is a bottom view thereof; and,

FIG. 5 is a front side view thereof, with rear, right, and left side views being mirror images thereof.

The broken lines illustrate a ceiling fan, and portions of the ceiling fan light kit. None of the broken lines form part of the claimed design.
